United States Patent Office

Des. 183,839
Patented Nov. 4, 1958

183,839

GEM SETTING OR SIMILAR ARTICLE

John L. Hudson, Detroit, Mich., assignor to
David I. Babitch, Detroit, Mich.

Application September 9, 1957, Serial No. 47,657

Term of patent 14 years

(Cl. D45—1)

Fig. 1 is a perspective view of a gem setting according to this invention mounted in a ring and having a gem mounted in the setting, the ring and gem being shown in dotted lines for illustrative purposes.

Fig. 2 is an enlarged elevational view of the setting, the gem and a fragment of the ring shank being shown in dotted lines for illustrative purposes.

Fig. 3 is an elevational view taken in the direction of arrow 3 of Fig. 2, the gem and a structural opening being shown in dotted lines for illustrative purposes only.

I claim:

A gem setting or similar article, as shown and described.
